CASING FOR SUPPOSITORIES

Josef Wadel, Hamburg, Germany

Application March 27, 1936, Serial No. 71,089
In Germany March 28, 1935

1 Claim. (Cl. 128—264)

This invention relates to a casing for suppositories and the object of the invention is to provide an improved casing with which it is possible to introduce the suppository in a hygienic and clean manner without it being necessary to touch the suppository itself.

As is well known, suppositories are generally reluctantly employed because, when they are introduced into the intestine, it is impossible to avoid soiling the fingers of the person by whom they are introduced. Further, the suppository must be held in the fingers which is also undesirable from a hygienic point of view.

These disadvantages are obviated by the present invention, by constructing the casing for the suppository in such a manner that it is unnecessary to touch the suppository in any way, and there is no possibility of soiling the fingers when it is introduced. This object is attained, in accordance with the invention, by making the casing in the form of a tube of thin rubber or the like which is closed at one end and resembles the finger of a glove. The closed end of a tube is drawn back inside the tube and the tube is sufficiently wide at the open end to allow a finger to be inserted. Thus not only does the casing protect the suppository but also allows it to be hygienically introduced, since, when the finger is inserted, the casing gradually slips over the finger, so that the suppository is thereby pushed out of the casing.

The present invention, therefore, provides a casing which not only fulfills the purpose of a covering for the suppository but, at the same time, enables the suppository to be introduced in an unobjectionable and hygienic manner. The casing fulfills this two-fold object without its efficiency as a casing being impaired or its cost being appreciably increased. The suppository can be taken from its box and introduced into the intestine without being touched at all and without any possibility of soiling the fingers.

A constructional embodiment of a casing, in accordance with the invention, is illustrated by way of example in the accompanying drawing, in which

Figure 1 is a view partly in section illustrating the casing with the suppository in it.

Figure 2 is a view showing the casing in pos-

tion ready for the introduction of the suppository, and

Figure 3 is a view showing the casing on the finger after the introduction of the suppository.

Referring to the drawing, the suppository *a* 5 lies in a part *b* of a tube of rubber which is closed at one end and resembles the finger of a glove. The part *b* is turned back inwards (i. e. partly turned inside out) so as to form a cup which is enclosed by the part *d* of the tube which is not turned in. The other end *c* of the tube is open and of sufficient width to allow a finger to be introduced into the opening.

In use, the suppository together with its casing is taken from the box in which it is packed, a 15 finger is inserted in the opening *c* and the suppository is pushed slightly out of the tube *b* as shown in Figure 2. The suppository is then introduced into the intestinal passage and the casing, beginning with the part *d*, gradually slips 20 over the finger which has been introduced until the suppository has been pushed right out of the casing and is introduced deeply into the intestine. After the introduction the tube or sheath which now encloses the finger can be stripped off 25 by rolling it up from the bottom and can then be thrown away. It is thus unnecessary to touch the suppository in any way, and there is also no possibility of soiling the finger.

The casing can be made of any suitable elastic 30 material which is sufficiently thin and is not attacked by the material of the suppository and is also sufficiently inexpensive.

I claim:—

The combination with a suppository for insertion into the body tracts; of an applicator for protecting said suppository in a hygienic manner against outside contact comprising a conically tapered flexible tube, the base of said tube being entirely open and the opposite end being entirely 35 closed and depressed into said tube to form a holder for said suppository entirely surrounding the same, said tube having such diameter and such length that the finger of a person may be inserted through said open end to contact the 40 walls of said pocket and push said suppository entirely therefrom against a normal resistance of the body tracts.

JOSEF WADEL.
